ASH TRAY

Anthony J. Glavin, 49 Marshall St.,
Medford, Mass. 02155

Filed Oct. 21, 1968, Ser. No. 14,098

Term of patent 14 years

Int. Cl. D27—03

U.S. Cl. D85—2

FIG. 1

FIG. 2

FIG. 3

FIG. 1 is a perspective view of an ash tray showing my new design;

FIG. 2 is a top plan view; and

FIG. 3 is a bottom plan view thereof.

The drawing figures are stippled to indicate contrast in appearance.

I claim:

The ornamental design for an ash tray, as shown and described.
